UNITED STATES PATENT OFFICE.

OWEN DAVID LUCAS, OF WESTMINSTER, LONDON, ENGLAND, ASSIGNOR TO VICKERS
LIMITED, OF WESTMINSTER, LONDON, ENGLAND, A BRITISH COMPANY.

PARACHUTE.

Application filed May 5, 1923. Serial No. 636,790.

To all whom it may concern:

Be it known that I, OWEN DAVID LUCAS, a subject of the King of Great Britain, residing at Vickers House, Broadway, Westminster, in the county of London, England, have invented certain new and useful Improvements in or Relating to Parachutes, of which the following is a specification.

This invention relates to parachutes, particularly such as are intended for pyrotechnic purposes where light or smoke signals or flares are to be shown in the air. The invention is however also applicable to life-saving parachutes carried by aircraft. When 10 parachutes are dropped they quickly attain a high velocity of descent such that the resistance offered by the parachute when it opens becomes so great as to sometimes break the fabric of which it is composed and the 15 chief object of the present invention is to obviate this disadvantage.

According to the invention the parachute is provided with means operating automatically to reduce the resistance offered by the 20 parachute when a predetermined resistance has been attained. These means preferably comprise a spring which is interposed between the load to be supported and a portion of the parachute fabric; this spring normally operates to hold the fabric in its position of maximum sustaining efficiency but when the resistance reaches the predetermined limit the said spring permits the 25 fabric to assume a position offering a smaller resistance the amount of which is approximately inversely proportional to the velocity of descent. The said fabric may be made in the form of an endless band the lower edge of which is connected by cords to a ring from which the load is suspended and the upper edge is connected by other cords to the aforesaid spring which in turn is connected to the load.

In order that the said invention may be clearly understood and readily carried into effect the same will now be described more fully with reference to the accompanying drawings, in which:

Figure 1 is a side view showing a parachute, constructed according to this invention, in its normal sustaining condition.

Figure 2 is a view similar to Figure 1 showing the parachute in the condition it

would theoretically assume when falling at infinite speed, and

Figures 3 and 4 are views similar to Figure 1 showing two modified forms of parachute.

A is the endless band (see particularly Figure 2) having a depth in the example shown, of about one third the diameter of this band when opened to form a cylinder as in Figure 2. The lower or outer edge of this band is connected by a number of cords $a^1, a^1 \dots$ to a ring A^1 and the upper $a^2, a^2 \dots$ or inner edge of this band is connected by a number of cords $a^2, a^2 \dots$ to a spring A^2 preferably composed of elastic strands. The lower end of this spring is connected to cords $a^{2x}, a^{2x} \dots$ passing through the ring A^1 and the ring carries depending cords $a^{1x}, a^{1x} \dots$ which are connected to the cords $a^{2x}, a^{2x} \dots$ at the points A^3 . The load is suitably connected to the said cords below their point of connection A^3 .

The lengths of the various cords are such that in the normal sustaining condition of the parachute the upper edge of the fabric band A is drawn downwards and inwards to cause the fabric to assume an annular shape with a large number of pockets as shown in Figure 1. The spring A^2 is stressed more or less according to the resistance offered by the fabric and as this resistance increases the inner edge of the fabric rises and further extends the spring without at first appreciably decreasing the sustaining power of the parachute. A critical point is, however, reached at which further rising of the said inner edge leads to a sudden drop in the sustaining power which critical point is designed to agree with the resistance beyond which it is not considered safe to subject the fabric. Further increase in the velocity of descent leads to a further raising of the inner edge and a consequent decrease in the resistance or sustaining power. This resistance is, however, sufficient to check the acceleration of the falling mass and to cause a decrease in the velocity and in consequence of the decreased resistance the spring A^2 re-acts to draw the aforesaid inner edge downwards towards its normal sustaining position.

Figure 3 shows a life-saving parachute in

- which means are provided for altering the position of the inner edge of the fabric A as desired during descent, these means comprising a hand line A⁴ which is attached 5 at one end to a ring a⁴ to which the cords a², a² . . . are connected and passes over a pulley a^{4x} carried by the ring a⁴ and over another pulley a^{5x} carried by a ring a⁵ to which the cords a^{2x}, a^{2x} . . . are attached.
- 10 By pulling on the free end of the said line A⁴ the parachutist can draw the aforesaid inner edge of the fabric A downwards below the position it would occupy under the action of the spring A² (which for convenience is shown as a spiral spring) and can thus increase the sustaining effect when it is required to clear an obstruction in landing.
- 15 Figure 4 shows an arrangement in which the aforesaid spring A² can be dispensed with, if the maximum velocity is not too high, by passing the cords a^{2x}, a^{2x} leading from the inner edge of the parachute over pulleys a⁶, a⁶ connected to the load A⁶ and connecting the ends to the ring A¹. In this 20 case a portion of the load is utilised for resisting the upward movement of the inner edge, the action in this respect being similar to that hereinbefore described with reference to the spring. Stops a⁷, a⁸ carried by the 25 cords a^{2x}, a^{2x} are adapted to co-operate with the pulleys a⁶, a⁶ to limit the upward and downward movements of these cords. The 30

aforesaid hand line A⁴ may also be employed in conjunction with this modification if desired.

35

What I claim and desire to secure by Letters Patent of the United States is:—

1. In a parachute, the combination of a fabric in the form of a cylindrical band, connections between the upper and lower 40 edges of said band and the load to be supported and means for permitting upward movement of said upper edge when a predetermined resistance has been attained.

2. In a parachute, the combination of a fabric in the form of a cylindrical band, connections between the upper and lower 45 edges of said band and the load to be supported and a spring in the connections between said upper edge and the load.

3. In a life-saving parachute the combination with the elements claimed in claim 1, of means for enabling the parachutist to alter the position of the upper edge of the 50 fabric as desired during the descent of the 55 parachute.

4. In a life-saving parachute, the combination with the elements claimed in claim 2, of means for enabling the parachutist to alter the position of the upper edge of the 60 fabric as desired during the descent of the 65 parachute.

OWEN DAVID LUCAS.
